O. D. MAPLE

MANIFOLD FOR INTERNAL COMBUSTION ENGINES

Filed March 27, 1925

Inventor

Orval D. Maple,

By *L. M. Thurlow*

Attorney

UNITED STATES PATENT OFFICE.

ORVAL DOUGLAS MAPLE, OF PEKIN, ILLINOIS.

MANIFOLD FOR INTERNAL-COMBUSTION ENGINES.

Application filed March 27, 1925. Serial No. 18,746.

To all whom it may concern:

Be it known that I, ORVAL D. MAPLE, a citizen of the United States, residing at Pekin, in the county of Tazewell and State 5 of Illinois, have invented new and useful Improvements in Manifolds for Internal-Combustion Engines; and I do hereby declare that the following is a full, clear, and exact description of the invention, which 10 will enable others skilled in the art to which it appertains to make and use the same.

This invention has reference to improvements in exhaust manifolds for internal combustion engines.

15 More particularly, the invention is directed to an exhaust manifold having a series of baffle plates disposed in the path of flow of the burned gases being expelled from the engine.

20 The object of my invention, broadly, is to interpose in the path of the burned discharging gases of an internal combustion engine a series of plates so designed and placed that, without constricting the passage beyond the cross sectional area of the discharge passage for free travel of the gas, the noise of explosions will be reduced to a minimum.

Another object is to reduce the noises of 30 explosions and to eliminate the "rumblings" due to such explosions that are particularly distressing in automobiles of the closed type and in automobiles of the touring variety when the same has been closed by the usual

35 "side curtains".

In the use of the common form of manifold and muffler a very unpleasant fluttering of the air in a car of the closed type is set up at certain engine speeds and which 40 emanate from the explosions. Besides, as well known, the noises of explosions even after passing through the muffler are quite often too evident.

I have found that by interposing properly 45 designed and placed members in the exhaust passage leading from the engine troubles of the nature described are reduced and almost entirely eliminated, and this is particularly true when such members are disposed within the manifold itself.

In the appended drawing forming part hereof,

50 Figure 1 is a vertical longitudinal section of an engine manifold involving my invention.

Figure 2 is a longitudinal section of the

same as viewed from above, the same being taken on line 2—2, Figure 1.

Figure 3 is an enlarged transverse section of the manifold taken on line 3—3, 60 Figure 1.

Figure 4 is an enlarged section of the same on line 4—4 of said Figure 1, and

Figure 5 is also an enlarged transverse section of line 5—5 of said Figure 1. 65

The numeral 1 designates a manifold having the usual ports 2, 3, 4 and 5 and a discharge end 6 having the customary exhaust pipe 7 leading to the muffler, not shown. 70

In designing my manifold it has been found expedient to station a baffle plate between adjacent ports and to that end the character 8 indicates one of said baffle plates in the main passage between the ports 2 and 75 3, one between the ports 3 and 4, and, in this instance, one of them together with a plate 9 of a slightly different type is placed between the ports 4 and 5.

The form of the plate 8 and its position 80 in the manifold is illustrated in Figure 3, it being observed that its edge is spaced from the walls of the passage but held at one or more points to secure it in place.

In Figure 4, the plate 9 referred to is 85 illustrated wherein it appears as a diaphragm closing the manifold passage except for a substantially central passage or opening 10, its relation to the plates 8, or any one of them, being substantially as indicated in Figure 3.

The space between each of the plates 8 and the wall of the manifold passage is, of course, designed to be such as will be correct in area for the requirements of free 90 discharge of the gases with no more back pressure created than would be set up by a muffler properly designed, and this is true also with respect to the openings in the plates 9. 100

In the present instance I have employed two of the plates 8 in that portion of the manifold having the closed end, the next being the type of plate 9, followed by a plate 8 but this may not be strictly adhered to. It is observed, however, that the baffle plates are so disposed that at least one of them lies between the ports of adjacent pairs so that practically an exhaust is carried into 105 each compartment separately. 110

In the passage at the discharge end of the device, or that end which directs the gases to

- the usual muffler there is stationed, alternately, several of both type of the plates 8 and 9. These are stationed between the port 5 and the said discharge end of the muffler 5 followed at the extreme end by two plates of a different form designed at 11. The latter are shown in Figure 5 and it may be seen that each extends from one wall of the passage to a point beyond the axis thereof 10 and from opposite sides whereby the gases in their movement must pass over one and under the other in a tortuous manner in somewhat the same way as provided by the mentioned plates 8 and 9.
- 15 It has been discovered that in an arrangement of this nature by separately "baffling" the exhausts from the ports 2, 3, 4 and 5 a surprising reduction of noises results, and that by the addition of plates in the discharge end of the muffler the noise of exhaust without a muffler is not disquieting. With the addition of a muffler, however, there is no sound apparent to one standing a few feet from the engine.
- 20 As a matter of fact the elimination of the muffler is possible and the noise of exhaust even when the engine is under considerable load is no more apparent than that noticed in the use of mufflers as used today. This 25 is stated as showing the efficacy of such an arrangement as described herein.

Although under test the placing of the baffle plates in the exhaust pipe toward the muffler end thereof yields somewhat of an 30 advantage in the reduction of noises the full benefit of such a structure is not realized until the plates are located in the manifold itself with the result named.

35 In providing for the proper size of openings through and around the baffle plates, in accordance with the rules governing the area of exhaust passages, my manifold is necessarily somewhat larger than the usual one for a given engine and therefore there 40 is a considerably larger space than usual into which the several exhausts are independently carried, these large and the separating plates providing for the deadening of 45 eliminated charges.

50 I claim:

- 55 1. In an exhaust manifold for internal combustion engines, a single conduit having a port leading into its passage from each combustion chamber of the engine, said passage increasing in cross sectional area from one end of the conduit toward the other in that portion thereof into which the said ports open, a baffle plate positioned in

the passage between each of the ports, and a series of baffle plates stationed in the passage between the discharge end of the conduit and the said series of ports, alternate plates of the last named plates being spaced from the walls of the passage, the others thereof being closed upon the walls and having openings therethrough inward from said walls.

2. In an exhaust manifold for internal combustion engines, a single conduit having a port leading into its passage from each combustion chamber of the engine, said passage increasing in cross sectional area from one end of the conduit toward its discharge end in that portion thereof into which said ports enter, a baffle plate positioned in the passage between each of the ports, and a series of closely arranged baffle plates stationed in the passage between the discharge end of the said conduit and that portion of the latter into which the ports lead the openings at said baffle plates alternating in position in successive plates whereby to create a tortuous path for the gases being discharged through said conduit.

3. In an exhaust manifold for internal combustion engines, a single conduit having a port leading into its passage from each combustion chamber of the engine, said passage increasing in cross sectional area from one end of the conduit toward its discharge end in that portion having the ports, a baffle plate positioned in the passage between each of the several ports and a series of baffle plates stationed in the passage between the discharge end of said conduit and the said series of ports arranged to cause the gases discharged through said conduit to follow a tortuous path.

4. In an exhaust manifold for an internal combustion engine, a conduit having a passage increasing in cross sectional area from one end of said conduit toward the discharge end thereof, spaced baffle plates stationed in said passage, there being a port leading into each space between said baffle plates, said passage between the position of the said baffle plates and the discharge end of the conduit being reduced in cross sectional area from the zone having the ports, and a series of baffle plates stationed therein having opening alternating in position whereby to provide a tortuous path for the discharge of gases.

In testimony whereof I affix my signature.

ORVAL DOUGLAS MAPLE.
